UNITED STATES PATENT OFFICE.

ALEXANDER KIRKWOOD, OF ELDERS FERRY, MISSISSIPPI.

METHOD OF PUMPING WATER OUT OF VESSELS.

Specification of Letters Patent No. 12,458, dated February 27, 1855.

To all whom it may concern:

Be it known that I, ALEXANDER KIRKWOOD, of Elders Ferry, in the county of Jackson and State of Mississippi, have invented 5 a new and Improved Mode of Pumping Water Out of Vessels; and I do hereby declare that the following is a full and exact description thereof.

The nature of my invention consists in 10 forcing water out at the bottom of a vessel, thereby avoiding the labor and expense of raising the water above the level of the water outside.

To enable others skilled in the art to make 15 and use my invention I will proceed to describe its construction and operation.

I first make a box and for proportion say 20 six inches wide four inches deep and fourteen inches long. Then put in two partitions dividing the box into three parts or 25 spaces as shown at A, B, and C, in the accompanying drawing and each partition must have an opening through it on which openings valves are applied as shown at d and e and in the bottom of the space b I 30 make a hole f; then turn the box over with the open part down; then into the hole f I insert a cylinder g into which must operate a piston h, the head of which must work air 35 tight; then fit the open part of the box to the bottom of the boat and by packing or otherwise make it to fit water tight excepting that under the edges of the box at the space a there must be openings made to admit water into that part of the box. The 40 box must be fastened down with clamps, screws, or otherwise, so that it can be removed from the spot when required. I then take up the box and immediately under the

space C bore a hole through the bottom of the vessel and when the water comes in from the outside then put the box back to its place and secure it there. This being done the pump is now ready for operation and as you raise the piston h the valve d opens 45 allowing the cylinder g to fill with water and on the downward motion of the piston h the valve d closes and the valve e opens allowing the water to force into the space c and through the hole out at the bottom of the vessel.

There could easily be a safety valve attached to close the hole in the bottom of the vessel when the pump is not in operation as described in my original specifications, but 50 that would be unnecessary because water from the outside cannot pass the valve e nor the valve d, neither can it pass through the cylinder g because the head of the piston h is packed and air tight.

In the accompanying drawing Figure 1 represents the pump with the cylinder fastened into the box, and Fig. 2 represents the box of the pump inverted so as to show the 55 operation of the valves.

What I claim as my invention and desire 60 to secure by Letters Patent is—

The attachment of the above described pump or of any ordinary force pump to the bottom of a vessel so as to force water out 65 at her bottom thereby avoiding the labor and expense of raising the water above the level of the water the vessel floats in.

A. KIRKWOOD.
